ATTORNEY

ROOF TREATING DEVICE

It is a primary object of the present invention to provide a holder capable of being attached along the ridge of a roof and containing a chemical which is gradually dissolved by moisture, so that the chemical will bleed from the holder and flow down the roof surface for cleaning the roof of stains and other discolorations resulting from various causes including mold and mildew, and for preventing the reoccurrence of such discoloration.

Another object of the invention is to provide a holder capable of containing slowly dissolving chemicals for coloring or restoring the original color of a faded roof.

Various other objects and advantages of the invention will hereinafter become more fully apparent from the following description of the drawing illustrating presently preferred embodiments thereof, and wherein:

BRIEF DESCRIPTION OF THE DRAWING

FIG. 1 is a fragmentary side elevational view, partly in section, showing a portion of a roof with one embodiment of the treating device applied thereto;

FIG. 2 is an enlarged fragmentary cross-sectional view, taken substantially along a plane as indicated by the line 2-2 of FIG. 1;

FIG. 3 is an enlarged cross-sectional view of the treating device, as shown in FIGS. 1 and 2, detached from the roof;

FIG. 4 is an enlarged fragmentary bottom plan view thereof;

FIG. 5 is a cross-sectional view of a portion of a single sloping roof and with another embodiment of the treating device applied thereto;

FIG. 6 is an enlarged fragmentary plan view of another embodiment of the treating device;

FIG. 7 is an enlarged cross-sectional view thereof, taken substantially along a plane as indicated by the line 7-7 of FIG. 6;

FIG. 8 is a fragmentary top plan view of another embodiment of the treating device;

FIG. 9 is a cross-sectional view thereof, taken substantially along a plane as indicated by the line 9-9 of FIG. 8, and

FIG. 10 is a cross-sectional view of still another embodiment of the treating device.

DESCRIPTION OF THE PREFERRED EMBODIMENTS

Referring more specifically to the drawing, one embodiment of the roof treating device, designated generally 12, is illustrated in FIGS. 1 to 4 and comprises two corresponding tubular members 13 each of which is filled with a suitable chemical 14, and each of which is provided with a multiplicity of apertures 15. The members 13 are illustrated in FIG. 3 as being of rectangular cross section with top and bottom walls substantially wider than the sidewalls thereof; however, said members 13 could be of various other cross-sectional shapes. The apertures 15 are formed in said top and bottom walls and sidewalls. The members 13 are preferably provided with imperforate or solid end walls 16, as indicated in FIG. 1.

The two members 13, constituting the chemical holder or dispenser, are connected to one another in spaced-apart substantially parallel relation by a web member 17 having side edge portions which are suitably secured to the members 13 in any conventional manner by an adhesive or stitching, not shown. The web 17 is formed of a flexible and porous material and extends from end-to-end of the members 13. The exteriors of the bottom surfaces of the members 13 are provided with transversely extending stripes of a coating material 18, as best seen in FIG. 4.

The dispenser 12 is of a length to extend from end-to-end of the ridge of a roof 19 with the web 17 engaging across the roof ridge, as seen in FIG. 2, and the members 13 resting one on each of the sloping sides of the roof adjacent to ridge thereof and secured thereto by the adhesive coatings 18. Additionally, the web 17 may be provided with spaced openings 20 for

receiving nails 21 which can be driven into the ridge of the roof for additionally securing the holder 12 thereon, especially in areas subject to strong winds.

The members 13 may be formed of various materials including certain metals and plastics and may be either rigid or flexible. The chemicals 14 may constitute various metal oxides or bleaching materials or a combination thereof which will dissolve gradually when exposed to moisture, so that rain water or dew will cause the chemicals to bleed gradually through the perforations 15 and flow down the sloping sides of the roof for cleaning the roof of discolorations resulting from various causes such as mold and mildew, which is especially common during prolonged periods of damp weather, and for also restoring the original color of a faded roof or for staining the roof a desired color.

FIG. 5 illustrated a slightly different embodiment of the treating device, designated generally 22, for use on a single sloping roof 23, and comprising a single tubular member 13', corresponding to one of the members 13, to one sidewall of which is connected a flexible tape 24 which may be secured by nails 25 to a vertical wall portion 26 of the building, adjacent the ridge of the roof, for cooperating with the adhesive coatings 18' to retain the member 13' in place on the roof 23 adjacent its upper edge or ridge. The treating device 22 will function in the same manner as heretofore described in connection with each of the tubular members 13.

Figs. 6 and 7 illustrate another embodiment of the roof treating device, designated generally 27, comprising two coarse woven fabric strips or pads 28, each of which is impregnated with the chemical or chemicals, and which are connected to one another in spaced-apart substantially parallel relation to one another by a web 29, corresponding to the web 17. The underside of the strips or pads 28 are provided with adhesive coatings 30 corresponding to the coatings 18. The treating device 27 is applied to a double sloping roof, such as the roof 19, in the same manner as the treating device 12 and functions in the same manner to accomplish the same results.

Figs. 8 and 9 illustrate a further embodiment of the invention comprising a roof treating device 31 comprising two strips of coarse mesh wire fabric 32, each of which is impregnated with the chemical or chemicals, and which are connected together in spaced-apart relation to one another along adjacent edges thereof by a web 33, corresponding to web 17. Strips of adhesive coatings 34, corresponding to the coatings 18, are applied to the undersides of the mesh wire fabric strips 32. The treating device 31 is applied and functions in the same manner as the roof treating device 12.

FIG. 10 illustrates a final embodiment of the roof treating device, generally designated 35, comprising two elongated relatively wide metal strips 36 which are connected together along adjacent longitudinal edges thereof by a web 37, corresponding to the web 17. The strips 36 are shown encased in a coating 38 of the roof treating chemical or chemicals. Adhesive coatings 39, corresponding to the coatings 18 are provided on the undersides of exposed portions of the strips 36 or on portions of the undersides of the coatings 38. In lieu of the chemical coatings 38, the strips 36 could be impregnated with the chemical. The treating device 35 is applied and functions in the same manner as the treating device 12.

It will be readily apparent that the treating devices 27, 31 and 35 could be made as single units for use on a single sloping roof in the same manner as the treating device 22. It will also be apparent that the treating devices 27, 31 and 35 could be made flexible to be sold in rolls to be cutoff to proper lengths corresponding to lengths of roofs to which said treating devices are to be applied.

Various other modifications and changes are contemplated and may be resorted to, without departing from the function of the scope of the invention.

I claim:

1. A device for treating a roof comprising in combination with a roof structure, an elongated holder containing a chemical capable of being dissolved by moisture, and means for at-

taching said holder along the ridge of said roof whereby moisture received by the holder will cause the chemical to be gradually dissolved and bled from the holder for cleaning and coloring the roof surface down which the chemical flows by gravity.

2. A roof-treating device as in claim 1, said holder comprising elongated transversely spaced holder sections, said attaching means including an elongated web disposed between and connected to said holder sections and adapted to engage along the ridge of the roof for supporting the holder sections one on either sloping side of the roof.

3. A roof-treating device as in claim 2, said attaching means additionally including adhesive coatings carried by the undersides of the holder sections for securing said sections to the sloping roof sides.

4. A roof-treating device as in claim 1, said holder comprising

ing an elongated perforated tubular container.

5. A roof-treating device as in claim 4, said attaching means including a tape secured along a portion of the container and adapted to be anchored to a building wall for supporting the container along the ridge of the sloping roof surface.

6. A roof-treating device as in claim 1, said holder comprising an elongated coarsely woven strip impregnated with the chemical.

7. A roof-treating device as in claim 1, said holder comprising an elongated mesh wire fabric strip impregnated with the chemical.

8. A roof-treating device as in claim 1, said holder comprising an elongated relatively wide strip coated with the chemical.
